UNITED STATES PATENT OFFICE.

ROBERT W. MATTOX, OF WEST TOCOI, FLORIDA.

THERMOMETER.

No. 926,993.

Specification of Letters Patent.

Patented July 6, 1909.

Application filed March 29, 1909. Serial No. 486,557.

To all whom it may concern:

Be it known that I, ROBERT W. MATTOX, a citizen of the United States, residing at West Tocoi, in the county of Clay and State of Florida, have invented new and useful Improvements in Thermometers, of which the following is a specification.

This invention relates to thermometers, and its object is to provide an improved device of this nature for indicating the temperature of the contents of a tank, such for instance as a still in which turpentine is treated to produce spirits of turpentine. In this process great care must be exercised to prevent the temperature of the turpentine from rising above a critical point at which it is liable to carbonize. It is customary, therefore, to arrange a thermometer passing horizontally through the wall of the still into the interior of the tank and having its outer portion bent upwardly and provided with the usual graduated scale. It is sometimes necessary to remove the thermometer for repairs or for storage when out of use, and to enable this to be readily accomplished the thermometer proper is inserted into a tube built into the wall of the still and having its closed inner end located inside the tank.

My invention relates to certain details of construction by which the thermometer is maintained in a central position in said tube, and also to means whereby an alarm is sounded when the temperature of the turpentine reaches the danger point; all as hereinafter set forth and particularly pointed out in the claims.

In the accompanying drawings, Figure 1 is a front elevation of my improved thermometer as seen from the outside of the still. Fig. 2 is a side elevation partly in section of the entire device, and Fig. 3 is a cross section.

The tank 1 which contains the turpentine is made of copper, and it is set in masonry 2 of suitable thickness. A tube 3 is built into the masonry in a horizontal position and extends through the wall of the tank, being externally screw-threaded at this point to receive the nuts 4, 5, which clamp the wall 1 tightly and form a fluid-tight joint. On the inner end of the tube, inside of the tank, there is screwed a cap 6 having an extension 7 smaller in diameter than the tube and made with a thin wall so that the heat of the turpentine can readily penetrate it. The tube is made of brass and the cap is preferably copper, while I prefer to make the nuts of bronze,

so that none of these materials will affect the turpentine injuriously.

Inside the tube 3 is a protecting sleeve 8 of any suitable metal, somewhat smaller than the tube 3 so as to be out of contact therewith and having near its inner end a projection 9, preferably a collar integral with the sleeve, which has an easy sliding fit in the bore of the cylindrical tube 3. The inner end 65 of the sleeve is screw-threaded internally to receive a tubular end piece 10 preferably made of steel and having a reduced portion 10' which is closed at its end and fits with a sliding fit into the extension 7 of the cap 6. 70 This end piece can be screwed in or out in the sleeve, to obtain the proper adjustment in length and cause the portion 10' to reach to the end of the extension. The collar 9 centers the sleeve when it is inserted into the 75 tube and insures the projection 10' entering the extension 7. The outer end of the sleeve is provided with a tubular plug 11 which is screwed into it and has a collar 12 preferably beveled to center the plug in the end of the 80 tube 3. A gland 13 is slipped over the outer end of the plug and bears against the collar, being internally screw-threaded to engage with threads on the outside of the tube 3. I prefer to form a countersink in the masonry 85 around the end of the tube to permit the gland to enter, so that its flange 14 may bear against the outside of the wall and clamp the tube firmly in position. A portion of the plug projects beyond the gland, and is preferably screw-threaded to receive the lower end of an upright casing 15 preferably V-shaped in cross section, with closed top and bottom.

The thermometer tube is of glass, and is 95 bent at right angles, as shown. The horizontal leg 16 is inserted through the plug 11 and passes through a guide 17 in the sleeve into the reduced portion 10' of the end piece 10, where it is preferably surrounded by a bath 100 of mercury to insure a quick and perfect transmission of the heat from the contents of the tank through the cap and end piece to the thermometer tube and its contained column of mercury. The upright leg 18 of the 105 glass tube extends up parallel with the casing, in the angle thereof. The adjacent surfaces of the interior of the casing are provided with the usual graduations, as shown. A glass cover 19 is placed over the casing, the 110 glass being held in a frame 20 which is preferably attached to the casing by a pin 21 at

the bottom entering a socket in the casing, and by a thumb nut 22 at the top overlapping the end of the frame. Fig. 2 shows how the cover can be removed when the nut 5 is unscrewed, the cover being shown as broken in two, with its upper part in place, and its lower part in the act of being removed. To protect the glass in transit, a metal door 23 is hinged to the casing, or to the 10 frame 20, and is provided with suitable fastening devices, such as the perforated lugs 24 to receive a padlock.

Two terminals are sealed into the thermometer tube, one at the lower end where it 15 will always be in contact with the mercury, and the other at the graduation indicating 306 degrees Fahrenheit, which is the danger point. The turpentine must not be permitted to go above 316 degrees, and therefore 20 306 is taken as the danger point in order that if the temperature rises to this point steps may be taken to reduce the heat before it gets to 316. In circuit with the two terminals is a battery 25 and an electric bell 26, 25 so that when the mercury rises to 306 the circuit will be closed and the bell will ring and warn the attendant to pull his fire.

Having thus described my invention what I claim is:—

- 30 1. The combination with a still, of a tube extending through the wall thereof, nuts on said tube clamping said wall, a cap screwed on the inner end of said tube and having a reduced extension, a sleeve inside said tube 35 and out of contact therewith, a tubular end piece screwed into the end of said sleeve and having a portion fitting into said extension, and a projection on said sleeve fitting the bore of the tube.
- 40 2. The combination with a still, of a tube extending through the wall thereof, nuts on said tube clamping said wall, a cap screwed on the inner end of said tube and having a reduced extension, a sleeve inside said tube, a 45 tubular end piece screwed into the end of

said sleeve and adjustable lengthwise therein and having a portion fitting the said extension, a tubular plug in the outer end of said sleeve having a collar centering said sleeve in said tube, and a gland screwed on the outside of said tube and bearing against said collar. 50

3. The combination with a still, of a tube extending through the wall thereof, nuts on said tube clamping said wall, a cap screwed on the inner end of said tube and having a reduced extension, a sleeve inside said tube, a tubular end piece screwed into the end of said sleeve and adjustable lengthwise therein and having a reduced portion fitting the said extension, a tubular plug in the outer end of said sleeve having a collar centering said sleeve in said tube, and a gland screwed on the outside of said tube and bearing against said collar, a casing attached to the outer end of said plug, and a thermometer tube having 65 one leg inserted in said sleeve and the other located in said casing.

4. The combination with a still, of a tube extending through the wall thereof, nuts on said tube clamping said wall, a cap screwed 70 on the inner end of said tube, a sleeve inside of said tube having a projection fitting the bore thereof, a longitudinally adjustable end piece for said sleeve, a casing supported on the outer end of said tube and provided with 75 a glass front and a graduated scale, a thermometer tube having a horizontal leg in said sleeve and a vertical leg in said casing, terminals sealed into the vertical leg of said tube, one of which is located at the danger point of 80 the scale, an electric alarm, and a battery in circuit with said alarm and said terminals.

In testimony whereof I have signed my name to this specification in the presence of two subscribing witnesses.

ROBERT W. MATTOX.
